United States Patent Office

Des. 175,521
Patented Sept. 6, 1955

175,521

BREAD BOX

Jean O. Reinecke, Oak Park, Ill., assignor to Federal Tool
Corporation, Chicago, Ill., a corporation of Illinois

Application April 11, 1955, Serial No. 35,441

Term of patent 14 years

(Cl. D44—1)

Fig. 1.

Fig. 2.

Fig. 3.

Fig. 4.

Fig. 1 is a front elevational view of a bread box embodying my new design;

Fig. 2 is a top plan view thereof;

Fig. 3 is a side view of the bread box; and

Fig. 4 is a back view thereof.

I claim:

The ornamental design for a bread box, substantially as shown.
